DESIGN FOR A STOOL OR SIMILAR ARTICLE

Glenn G. Crandall, Springfield, Mass.

Application July 24, 1943, Serial No. 110,745

Term of patent 7 years

To all whom it may concern:

Be it known that I, Glenn G. Crandall, a citizen of the United States, residing at Springfield, in the county of Hampden and Commonwealth of Massachusetts, have invented a new, original, and ornamental Design for a Stool or Similar Article, of which the following is a specification, reference being had to the accompanying drawing, forming part thereof.

Fig. 1 is a top plan view of a stool, showing my new design; and

Figs. 2, 3 and 4 are perspective views of different adjacent sides of the stool.

I claim:

The ornamental design for a stool or similar article, as shown.

GLENN G. CRANDALL.
